Francis D. Cannon
his Atty.

UNITED STATES PATENT OFFICE.

GEORGE B. CANNON, JR., OF BROOKLYN, NEW YORK.

UMBRELLA.

1,316,421.

Specification of Letters Patent. Patented Sept. 16, 1919.

Application filed April 18, 1919. Serial No. 290,993.

To all whom it may concern:

Be it known that I, GEORGE B. CANNON, Jr., citizen of the United States, and resident of Brooklyn, in the county of Kings 5 and State of New York, have invented certain new and useful Improvements in Umbrellas, of which the following is a specification.

This invention relates to umbrellas, and 10 particularly to a type of umbrella, the frame of which including the stick, may be formed of wire.

The general object of the invention is to produce an inexpensive umbrella frame 15 which can be readily formed of wire, one of my special objects being to reduce as much as possible the amount of wire necessary to form the stick-portion of the umbrella. According to my invention, the 20 complete frame of the umbrella can be formed of a plurality of wires, lying substantially parallel with each other, these wires being bent so as to form the stick-portion, ribs, handle and stretchers.

25 The invention consists in the features hereinafter described, all of which contribute to produce an efficient umbrella.

A preferred embodiment of my invention will be particularly described in the following specification, while the broad scope 30 of my invention will be pointed out in the appended claims.

In the drawing, which illustrates a preferred embodiment of my invention,

35 Figure 1 is a vertical section through the open umbrella;

Fig. 2 is a side elevation showing the umbrella in its folded state;

Fig. 3 is a side elevation showing the 40 umbrella frame at one stage in its manufacture;

Fig. 4 is a side elevation of the handle showing a modified form of this part;

Fig. 5 is a detail section taken at the end 45 of a rib and illustrates how the ribs hold the edges of the umbrella cover.

Referring more particularly to the parts, the umbrella frame comprises a central stick-portion 1, which is preferably formed of a 50 plurality of wires 2 lying side by side. These wires are preferably substantially straight and disposed in parallel relation with each other. At the lower end of the stick-portion 1, the wires 2 are bent in any suitable manner so as to form a handle 3.

The upper ends of the wires 2 are con-

nected together, for example, by forming a twist 4, beyond which point the wires have integral extensions which extend upwardly and outwardly so as to constitute the ribs 5 of the umbrella.

From the stick-portion 1, preferably adjacent the upper end of the handle 3, stretchers 6 extend upwardly and connect with the ribs. These stretchers are preferably formed integrally from the wires 2. In order to do this, the lower ends of the wires are preferably bent outwardly at their lower ends as at 7 in Fig. 1, and then extend upwardly alongside the stick-portion to form an enlargement constituting a handle portion 3.

At the upper end of the handle portion the wires are attached to the stick-portion 1. This is preferably accomplished by means of a twist 8 formed by coiling the different wires around the stick-portion. From the coils which form this twist, the wires extend upwardly and outwardly in an inclined direction so as to form the stretchers 6.

Any suitable means may be provided for connecting the stretchers 6 to the ribs 5. This is preferably accomplished by forming a slight lateral bend or socket 9 in each rib which receives a hook 10, (see Fig. 2), formed on the end of each stretcher.

In manufacturing the umbrella frame, I prefer to proceed in the manner indicated in Fig. 3, that is to say, I lay a plurality 90 of wires of equal length side by side and form a twist 4 by plaiting or coiling the wires together, and this twist eventually forms the upper end of the stick-portion. The extensions 11, which lie at the right 95 of the twist 4, in Fig. 3, are then provided with bends such as the bend 9, adapting them to operate as ribs.

The wires should be of resilient material so that in the complete umbrella, the rib 100 wires unite with the twist 4 through a curved portion 12, see Fig. 1. The extensions 13 of the wires which lie on the left of the twist 4, in Fig. 3, are then bent so as to form the handle and the stretchers.

105 The cover 14 of the umbrella is preferably composed of an inexpensive waterproof material such as waterproof paper.

The umbrella illustrated, has four ribs, but obviously there may be more or less of the ribs, as may be desired.

The cover simply lies extended upon the

ribs when the umbrella is open. The edges of the cover are attached to the umbrella ribs by means of reinforcing eyelets 15, see Fig. 5, and the ends of the ribs are bent 5 around so as to form eyes 16 engaging these eyelets. Except for the edge attachments, the cover is unattached to the ribs.

When the umbrella is folded up, it has the general appearance indicated in Fig. 2, 10 the cover lying in the space between the ribs. In order to open the umbrella, the rib ends are simply pulled outwardly so as to stretch the cover and in doing so, the hooks 10 are applied to the bends or sockets 9, thereby 15 holding the ribs in the bowed shape.

Instead of bending the wires to form a handle of the tapered form shown in Fig. 1, I may provide a modified form for the handle, for example, such as that shown in 20 Fig. 4, in which the wires at the lower end of the handle are bent upwardly so as to form an enlargement composed of wire extensions 17 producing loops 18 in the wire, coöperating to form the handle, the wires 25 being made secure by a twist 19 of the wires where the handle wires 17 unite with the stick-portion 20, said stick-portion being composed, as in the preferred form, of a plurality of substantially straight parallel 30 wires 21.

It is evident, that according to my invention, the umbrella frame can be formed of a plurality of wires, each of which forms a portion of the handle, a part of the stick-portion, and a rib and stretcher of the umbrella, but it should be understood that I do not limit myself to making all of these parts in one piece, as it is obvious that if desired, a certain number of the parts could be made 35 integral, while separate wires could be employed to form the other part or parts of the frame. For example, the stretchers could readily be formed of pieces of wire separate from the wires that form the handle.

40 It is understood that the embodiment of the invention described herein, is only one of the many embodiments this invention may take, and I do not wish to be limited in the practice of the invention, nor in my claims, 45 to the particular embodiment set forth.

What I claim and desire to secure by Letters Patent is:

1. An umbrella frame comprising a central stick-portion composed of a plurality 55 of wires, the upper ends of said wires extending upwardly and outwardly and constituting umbrella ribs, said wires at the lower end of said stick portion being bent to form a handle; and stretchers extending from 60 said stick-portion and connecting to said ribs.

2. An umbrella frame comprising a central stick-portion composed of a plurality of wires, the upper ends of said wires extending 65 upwardly and outwardly and constitut-

ing umbrella ribs, said wires at the lower end of said stick portion being shaped into vertical loops, said loops coöperating to form a handle for the stick-portion, and stretchers extending from said stick-portion 70 and connecting to said ribs.

3. An umbrella frame constructed of a plurality of wires disposed side by side to form the stick-portion of the umbrella, the upper ends of said wires extending upwardly and outwardly from the upper end of the stick-portion to form the umbrella ribs, the lower ends of said wires being bent 75 to form a handle, and extending upwardly and outwardly from a point adjacent the upper end of the handle, and connecting with the ribs so as to constitute the umbrella stretchers.

4. An umbrella frame comprising a central stick-portion composed of a plurality 85 of wires, said wires being connected together adjacent the upper end of said stick-portion, and extending upwardly and outwardly so as to constitute umbrella ribs, the lower ends of said wires being bent to 90 form an enlargement constituting a handle for the umbrella; and stretchers connecting said stick-portion with said ribs.

5. An umbrella frame comprising a central stick-portion composed of a plurality of 95 wires, said wires being connected together adjacent the upper end of said stick-portion and extending upwardly and outwardly so as to constitute umbrella ribs, the lower ends 100 of said wires being bent to form vertically elongated loops coöperating to form a handle for the umbrella, the upper ends of said loops being attached together; and stretchers extending from a point adjacent the upper 105 ends of said loops and connecting with said ribs.

6. An umbrella frame comprising a central stick-portion composed of a plurality of wires extending side by side, said wires being connected together adjacent the upper end of said stick-portion, and extending upwardly and outwardly so as to constitute umbrella ribs, the lower ends of said wires being bent to form a handle for the umbrella, said wires being attached to the 110 stick-portion adjacent the upper end of said handle, and having integral extensions extending upwardly and attached to said ribs, and constituting stretchers.

7. An umbrella frame comprising a central stick-portion composed of a plurality of substantially straight wires extending substantially parallel with each other, said wires having a twisted portion adjacent the upper end of the stick-portion at which 115 said wires are connected together, said wires beyond said twisted portion extending upwardly and outwardly so as to constitute umbrella ribs, the lower ends of said wires being bent to 120 form loops coöperating to 125

130

form a handle, being connected together at the upper portion of the handle, extending upwardly from the upper portion of said handle, and connecting with said ribs so as 5 to constitute stretchers.

8. An umbrella frame comprising a central stick-portion composed of a plurality of substantially straight wires extending substantially the entire length of said stick-portion, said wires being connected together adjacent the upper end of said stick-portion and extending upwardly and outwardly from the upper end of said stick-portion so as to constitute umbrella ribs, said wires 10 being bent at the lower end and extending along the side of said stick-portion so as to form a wire handle, the wires whereof are attached to the stick-portion, and having integral extensions extending upwardly and 15 outwardly, and connecting with said ribs to constitute stretchers.

20 Copies of this patent may be obtained for five cents each, by addressing the "Commissioner of Patents, Washington, D. C."

9. An umbrella frame comprising a central stick-portion composed of a plurality of substantially straight wires extending substantially the entire length of said stick-portion, a twist of the wire connecting said wires together adjacent the upper end of said stick-portion, said wires extending upwardly and outwardly from said twist and constituting umbrella ribs, the lower ends 25 of the wires of said stick-portion being bent so as to form a handle with a twist of wire around the stick-portion adjacent the upper end of the handle, said wires having integral extensions extending upwardly and 30 outwardly from said last named twist and connecting with the ribs to constitute stretchers.

Signed at New York city in the county of New York and State of New York this 40 14th day of April, A. D. 1919.

GEORGE B. CANNON, JR.
